UNITED STATES PATENT OFFICE

169,801

CRIBBAGE BOARD OR SIMILAR ARTICLE

Anthony V. Capodanno, North Attleboro, Mass.

Application January 26, 1953, Serial No. 23,295

Term of patent 14 years

(Cl. D34—5)

To all whom it may concern:

Be it known that I, Anthony V. Capodanno, a citizen of the United States of America, residing at 55 Grant Street, North Attleboro, Massachusetts, have invented a new, original, and ornamental Design for a Cribbage Board or Similar Article, of which the following is a specification, reference being had to the accompanying drawings, forming a part thereof, and wherein

Fig. 1 is an isometric view of a cribbage board showing my new design;

Fig. 2 is a rear elevational view; and

Fig. 3 is an end elevational view looking from the left hand end of Fig. 2.

I claim:

The ornamental design for a cribbage board or similar article, substantially as shown.

ANTHONY V. CAPODANNO.
